H. A. BALLARD

SPRING SHANK HAMMER MECHANISM

Filed July 28, 1922

Patented Apr. 27, 1926.

1,582,625

UNITED STATES PATENT OFFICE.

HARRIE A. BALLARD, OF BOSTON, MASSACHUSETTS, ASSIGNOR TO THE PHONOHARP COMPANY, OF EAST BOSTON, MASSACHUSETTS, A CORPORATION OF MAINE.

SPRING-SHANK-HAMMER MECHANISM.

Application filed July 28, 1922. Serial No. 578,084.

To all whom it may concern:

Be it known that I, HARRIE A. BALLARD, a citizen of the United States, residing at Boston, in the county of Suffolk and State 5 of Massachusetts, have invented new and useful Improvements in Spring-Shank-Hammer Mechanism, of which the following is a specification.

This invention relates to playing mechanism 10 for musical instruments and has more particular relation to a hammer action by which the various strings or other sounding elements may be sounded.

According to this invention each hammer 15 mechanism comprises an axially slidable plunger constructed to engage a spring hammer consisting of a leaf spring carrying at its free end a string-striking element or head located at a substantial distance from the 20 plunger engagement therewith. A cushion is provided to limit without noise the motion of the plunger in either direction. The fixed end of the spring is made fast in such position that it urges the plunger into inoperative position when pressure on the 25 plunger is released.

The spring shank of the hammer and the plunger are so engaged as to prevent lateral movement of one relative to the other 30 and so that the plunger, when in an operated position, limits the movement of that portion of the spring shank which is engaged by it defining a node of vibration for the spring shank of the hammer, the hammer 35 being free to vibrate against the string.

For a more complete understanding of this invention, together with further objects, advantageous details and combinations of parts, reference may be had to the accompanying drawing showing the invention as applied to an instrument of the zither type. In these drawings,

Figure 1 is a fragmentary plan of the instrument showing the invention applied thereto, portions being broken away.

Figure 2 is an elevation of the same with parts broken away.

Figure 3 is a fragmentary vertical section on line 3-3 of Figure 2 showing a 50 single hammer action in elevation.

Figure 4 is a perspective of an actuating plunger.

Referring to the drawings, 1, in Figure 3, indicates a portion of the instrument frame

having a shoulder 2 at one end over which 55 passes the ends of the strings shown at 3. The mechanism of the invention is applied to this frame, and, as shown, comprises a pair of end plates 4 suitably fixed thereto, these plates being closed off at their ends 60 remote from the frame 1 by means of an end plate 5. The end plate 5 has its upper end turned inwardly to form a supporting flange 6 for the reception of a keyboard strip 7 which is made fast on its upper face. This 65 strip 7 is provided with perforations as 8 for the slidable reception of hammer-actuating plungers 9, one plunger being provided for each string or set of strings intended to be sounded in unison.

As shown in this embodiment the strings 70 designed to be actuated by the mechanism are arranged in pairs and are intended to be struck simultaneously. A single string or more than two might be employed, however, 75 according to the particular construction of the instrument to which the mechanism is to be applied. Between the end frames 4 and beneath the keyboard 7 is fixed a support or bar 10 which is shown as angular in 80 cross section to provide an upwardly extending ledge 11 along the edge remote from the frame 1. Made fast to the top of this ledge 11 is a guide strip or plate 12 which has a series of perforations 13, herein shown 85 as of angular cross section, to slidably receive the lower ends of the plungers 9. Beneath the plate 12 a strip of felt 23 is shown as applied to the upper face of the support 10 adjacent the ledge 11. This felt strip is 90 for the purpose of receiving the end of each plunger 9 when it is depressed into string-striking position so as to limit its downward stroke in a noiseless manner. As 95 shown each plunger is formed of sheet material, the lower portion 14 being formed angular, while the upper portion may, if desired, be formed cylindrical as at 15 to pass through cylindrical openings in the keyboard, and an actuating button 16 may be 100 formed or made fast to the upper end of each plunger. One side or leg of the angle portion 14, as 17, is slotted at 18 for the reception of the spring shank 19 of the hammer which is retained in position within the slot by means of a hook 20 extending from the other leg, substantially parallel to the leg 17, and engaging over the edge of the

spring shank 19. Above the leg 17 and hook 20 may be positioned a washer 21 of yieldable material such as felt to limit the upward motion of the plunger by impingement 5 on the keyboard 7. The spring shank 19 is bowed outwardly and then downwardly as shown at 25 and passes between the outer face of the support 10 and a clamping strip 26 fixed thereto in position to retain the 10 various hammers in correct relative positions and in correct relation to the strings of the instrument. The spring shank passes beneath the hook 20 and through the slot 18 at a point intermediate its ends, and the 15 forward end of the shank carries at a substantial distance from its engagement by the plunger a string-striking head 30. By depression of the plunger 9, until it engages the cushion 23, the spring hammer 19 is so 20 flexed so as to bring the head 30 by its momentum down against the string, the resiliency of the shank permitting the head to vibrate against the strings for a considerable time after depression of the plunger. The 25 node of vibration of the free end of the hammer is at the slot 18 in the plunger, this slot being but slightly wider than the shank is thick. When the plunger is released the spring shank 19 raises it until the washer 30 35 engages the strip 7, and in order to prevent vibration of the hammer head when in inoperative position, it is cushioned and stopped by a pad 27 fixed to the lower face of a rebound board 28 which is supported by 40 resilient arms 29 from the lower face of the keyboard 7 or the plate 5, if desired these arms being integral with the flange 6.

From this description it will be apparent that inasmuch as the plunger slides in spaced 45 guides which hold it against lateral movement and the end of each spring hammer is fixed, any lateral movement of the hammer heads is prevented by the engagement of the hook 20, and the end wall of the slot 18 with the side edges of the hammer shank 19.

While this invention has been shown as applied to a stringed instrument it is evident that it could also be applied to other instruments in which the notes may be 50 sounded by a hammer action, such, for example as a xylophone. The term "string" as used in this application, therefore, is intended to indicate broadly one or more strings or sounding elements which are 55 designed to be struck in unison to produce the desired note.

Having thus described an embodiment of this invention it should be evident that many changes and modifications might be made 60 therin without departing from its spirit or scope as defined by the appended claims.

I claim:

1. In a musical instrument, an axially slide- 65 able plunger, a spring hammer engaged at opposite sides intermediate its ends by said

plunger, and means for fixing one end of the spring shank of said hammer leaving the head end of said hammer free.

2. In a musical instrument, an axially slide- 70 able plunger having a transverse opening therethrough, a spring hammer having its spring shank passed through said opening, and means for fixing one end of said shank leaving the head end of said hammer free.

3. In a musical instrument, an axially slide- 75 able plunger having a sheet metal shank portion provided with a slot, a spring hammer having a leaf spring shank portion passed through said slot between its ends, the sides of said slot closely engaging said spring 80 shank, and means for fixing one end of said spring shank leaving the head end of said spring hammer free.

4. In a musical instrument, an axially slide- 85 able plunger having a sheet metal shank portion provided with a slot, a spring hammer having a leaf spring shank portion passed through said slot between its ends, the sides of the said slot closely engaging said spring 90 shank means for fixing one end of said spring shank leaving the head end of said spring hammer free and means for retaining said spring shank within said slot.

5. In a musical instrument, an axially slide- 95 able plunger having a sheet metal shank portion provided with a slot, a spring hammer having a leaf spring shank portion passed through said slot between its ends, the sides of said slot closely engaging said spring 100 shank, means for fixing one end of said spring shank leaving the head end of said spring hammer free, and means for retaining said spring shank against lateral motion in said slot.

6. A device of the class described comprising a support having a guide opening, a plunger axially slideable through said opening, a pad against which the end of said plunger may impinge and furnish a noiseless stop therefor, a leaf spring made fast at 105 one end to said support and engaged between its ends by an intermediate portion of said plunger, and a striking element carried by the other free end of said spring.

7. In combination, in a stringed musical 110 instrument, a bar angular in cross section constructed to be made fast transverse to the strings of the instrument, a strip of cushioning material carried by one arm of said bar, a strip carried by the other arm of said bar 115 and spaced from said cushioning strip and having guide openings therethrough spaced to correspond with said strings, a plunger axially slideable through each guide opening into and out of contact with said cushioning 120 strip, a spring element for each plunger 125 fixed at one end to said bar, engaged by its plunger intermediate its ends and having its free end extending over the corresponding string of said instrument, and a head ele- 130

ment carried by each free end in position to strike the strings when its plunger is depressed into contact with said cushioning strips.

5 8. In a device of the class described, a hammer actuating plunger having a slotted portion through which a hammer-carrying element may pass, and means for retaining said element within said slot.

10 9. In a device of the class described, a hammer-actuating plunger having a portion of angular cross section, one of the legs of the angle having a slot for the reception of a hammer-carrying element, and a hook extending from the other leg in position to retain the element in said slot.

15 10. In a musical instrument, a plunger having a portion of angular cross section, one of the legs of the angle having a slot therethrough, a spring hammer having its 20 spring shank extended through said slot and closely engaged by the walls thereof, and an element projecting from the other leg of the angle for retaining said spring shank 25 against lateral movement within said slot.

11. In a musical instrument, a spring hammer having a spring shank portion, a plunger engaging said shank at a point intermediate the ends thereof and defining a node 30 of vibration of said shank, and means for fixing one end of said shank leaving the head end free.

12. The combination with a spring hammer of an actuating plunger therefor having a slot formed to closely receive the shank of said hammer and defining the node 35 of vibration thereof, and means for retaining said shank in said slot.

13. The combination with a spring hammer, of an actuating plunger therefor having a slot formed to closely receive the shank of said hammer, and defining the node 40 of vibration thereof, means for retaining said shank in said slot, and means for preventing lateral movement of said spring shank within said slot.

14. In a musical instrument, a series of spring hammers, and common means for detachably clamping one end of each of said hammers in fixed position. 50

15. In a musical instrument, a support, a series of spring hammers, and a strip attachable to said support in position to clamp one end of each of said hammers thereagainst leaving the head ends of said hammers free. 55

16. In a stringed musical instrument, a support extending laterally of the springs at one end, a series of spring hammers having resilient shanks positioned against said support, and a bar extended along said support for clamping the hammers in position. 60

17. In a stringed musical instrument, a pair of spaced guide members, a plurality of plungers guided for axial movement by said members, and hammers actuated by movement of said plungers for striking the strings of the instrument. 65

18. In a stringed musical instrument, a pair of spaced guide members, plungers guided by said members and spring hammers engaged by said plungers between said members and actuated to strike the strings of said instrument on movement of said plungers. 70

19. In a stringed musical instrument, a pair of spaced guide members, a plurality of plungers guided for axial movement by said members, hammers actuated by movement of said plungers for striking the strings of the instrument, and a stop for limiting the motion of said plungers to striking position. 75

20. In a stringed musical instrument, a pair of spaced guide members, plungers guided by said members, and spring hammers engaged by said plungers between said members and actuated to strike the strings of said instrument on movement of said plungers, and a stop for limiting the motion of said plungers to striking position. 80

45 In testimony whereof I have affixed my signature.

HARRIE A. BALLARD.
